UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

PNEUMATIC-TURBINE DRILL.

1,099,392.

Specification of Letters Patent.

Patented June 9, 1914.

Application filed September 18, 1913. Serial No. 790,575.

To all whom it may concern:

Be it known that I, REINHOLD A. NORLING, a citizen of the United States, and a resident of Aurora, in the county of Kane and State 5 of Illinois, have invented certain new and useful Improvements in Pneumatic-Turbine Drills; and I do hereby declare that the following is a full, clear, and exact description thereof, reference being had to the 10 accompanying drawings, and to the letters of reference marked thereon, which form a part of this specification.

This invention relates to improvements in pneumatic turbine drills and more particularly to an improved construction for a 15 pneumatic turbine motor adapted to operate a drilling or like tool.

In the construction of a drilling tool embodying my invention, it is proposed to produce a highly efficient and durable tool of 20 exceptional power and extreme lightness of weight. To gain this end, I provide a high speed turbine rotor mounted in suitable anti-friction bearings, a proper tool-holding 25 spindle, and speed reducing and power transmission interposed between the rotor and tool spindle, so constructed and arranged as to afford perfect running balance in all 30 parts, thus eliminating to a large extent the loss of power by friction. In addition, I propose to provide a controlling means particularly designed with a view to affording perfect ease and convenience in the manipulation of the tool, and the most efficient 35 utilization of the power at hand.

My invention consists of the features hereinafter fully described and more particularly pointed out in the appended claims.

In the accompanying drawings Figure 1 40 is a longitudinal section of the drill embodying my invention; Fig. 2 is a view in elevation of the drill with a portion of the gear casing broken away and parts therein shown in section; Fig. 3 is a detailed view in elevation of the spindle removed from the casing, showing the construction of the same; Fig. 4 is a cross-sectional view, taken on line 4-4 of Fig. 1; Fig. 5 is a cross-sectional view, taken on line 5-5 of Fig. 1; Fig. 6 45 is a view in cross-section, taken on line 6-6 of Fig. 1; Fig. 7 is a view in cross-section, taken on line 7-7 of Fig. 2, showing the construction of the controlling lever for the throttle valve; Fig. 8 is a cross-sectional

view, taken on line 8-8 of Fig. 7, showing 55 the structure of the throttle valve.

Referring to the drawings: The device embodying my invention comprises in the main the combination of elements as follows, to wit;—a rotor casing 1, within which 60 is formed the air inlet passages, nozzles, and rotor chamber 1^a, the latter containing the rotor or turbine wheel 2, a gear casing 3, containing the rotatable tool spindle 4 which carries a train of speed reducing or reduction gears interposed between the turbine shaft 5 and fixed internal gear 6 at the lower part of the gear casing; a spindle support 7, separating the rotor chamber and the gear casing; a threaded collar 8 engaging 65 the adjacent marginal flanges of said rotor casing 1 and the gear casing 2, a handle 9 secured to the upper portion of the rotor casing, and a throttle valve mechanism 10 mounted within the rotor casing. 75

Referring now more in detail to the construction of the above named elements. The rotor or turbine wheel 2 is rigidly secured to the turbine shaft 5 adjacent to its upper extremity, said wheel being provided with a 80 tapered bore which engages a similarly tapered portion 5^a of the shaft. A washer 11 is mounted upon the shaft and bears against the turbine wheel, the same being interposed between said turbine wheel and a nut 12 engaging 85 a threaded portion of the shaft and bearing against the said washer. The said rotor 2 is adapted to turn within the before-mentioned rotor chamber 1^a formed in the lower portion of the rotor casing 1. The periphery of the rotor is provided with a plurality of radially arranged and evenly spaced peripheral blades or buckets 2^a (Figs. 1 and 4), the said blades being provided with uniformly concaved surfaces 2^b each of 95 which is adapted to receive an impulse from jets of the motive fluid directed against them, in a manner hereinafter to be described.

The upper extremity of the turbine shaft 100 is reduced in size and is mounted within an anti-friction roller bearing which rests within an axial bore in the top or end portion of the rotor casing, and is constructed as follows: A plurality of rollers 13 (Fig. 1) are 105 held within a retaining cage 13^a, said rollers and cage surrounding the shaft. A bushing 14 fits within the axial bore 1^b and incloses

the said roller bearing, the said bushing acting as a bearing surface for the rollers 13. The bearing cage and bushing abut at their ends against a thrust plate 15 and a thrust block 16, the said thrust plate resting upon the shoulder 1^c formed at the base of the said bore 1^b and the said thrust block resting loosely in the upper portion of said bore. The thrust block is held in place by the handle 9, the base plate 9^a of which covers the entire upper surface of the rotor casing, and through which extend bolts 9^b which are anchored in the rotor casing.

Lubrication is supplied to the roller bearing by means of an annular channel 17 which surrounds the bushing 14 and communicates with an oil hole 17^a extending through the wall of the rotor casing. A screw plug 18 engages the oil hole and is adapted to be screwed inward, thus forcing a small quantity of grease which is contained in the said oil hole 17^a and the channel 17 into the bearing, through a plurality of apertures 14^a in the bushing 14. Within the gear casing 3 and surrounding the turbine shaft 5 is rotatably mounted the before mentioned tool spindle 4 which is constructed as follows: Two spindle disks 19 and 20 are rigidly secured together and at considerable distance apart, by means of a spindle sleeve 21 the ends of which fit within annular channels forced in the adjacent peripheral margins of the disks, by means of bolts 22 (Fig. 3) extending through the disks at points diametrically opposite each other, and adjacent to the peripheries of the disks and to the inner surface of the spindle sleeve. The upper spindle disk is provided with an upwardly extending bearing flange 19^a (Fig. 1), which forms a continuation of a central bore of the said disk through which extends the turbine shaft 5. The said bearing flange 19^a engages an anti-friction bearing 23 mounted within the spindle bearing support 7. The said bearing support comprises an annular disk the margin of which is mounted within grooves formed in the adjacent inner margins of the gear case and rotor case and rigidly held in position by the threaded collar 8, which acts to clamp the said bearing support in place as well as to connect the said rotor and gear casings. The said roller bearing 23 rests within an annular space formed within an enlarged central portion of the said bearing support, and comprises a bushing 24 surrounding a plurality of rollers 25 which bear against the outer and inner surfaces of the bearing flange and the bushing, respectively, and a bearing thrust plate 24^a held in the upper portion of the depression. The rollers 25 are each provided with an annular peripheral groove 25^a adapted to admit and engage an annular wire band or retaining collar 26 closely surrounding the

flange or journal 19^a, said wire band being adapted to retain the rollers in place when the spindle is removed from the bearing. The lower ends of the rollers rest upon the spindle thrust bearing plate 27 which is fitted within an annular space immediately below the roller bearing 23 and held from movement by means of a shoulder 7 formed in the bearing support. Immediately below the said plate 27 is an annular bearing retainer 28 forming a circular ball race or groove containing a series of bearing balls 28^a arranged in a circle between the members 27 and 19 and surrounding the spindle 25. The said bearing retainer is mounted within a space separating the upper surface of the spindle disk 19 and the adjacent surface of the spindle bearing support 7, there being grooved ball races formed in said upper surface of said spindle disk and in the thrust plate 27, which are engaged by the bearing balls 28^a. Integral with or fixed to the lower spindle disk 20 and in axial alignment with the turbine shaft is a spindle sleeve 29 (Figs. 1 and 2), the same consisting of a tubular shaft extending downwardly from the central portion of said disk and through and beyond the lower extremity of the gear casing (Fig. 1). The said spindle sleeve 29 is provided with a roller bearing 30 (Fig. 1) comprising peripherally grooved rollers 30^a surrounding the spindle sleeve at substantially its central portion and having an annular collar or wire guide 30^b in engagement with the grooves, a bushing 30^c surrounding the rollers 30^a and fixed within an annular space formed in the lower portion of the gear casing adjacent to its extremity, and two thrust plates 30^d, 30^d surrounding the spindle sleeve at the ends of the rollers 30^a and between which the same are located. This bearing is very similar in construction to the upper spindle bearing and hence need not be further described. Upon the surface of the spindle sleeve and immediately above the spindle bearing, is formed an annular collar 29^a having a downwardly facing surface adapted to engage the upwardly facing surface of the adjacent thrust plate 30^d of the bearing 30, and acting to limit the endwise movement of the spindle. At the lower extremity of the gear casing through which extends the spindle sleeve is provided a stuffing box 31 surrounding the said sleeve and in screw-threaded engagement with an internally threaded portion of the gear casing 3. The stuffing box retains within an annular space a packing ring 31^a, its purpose being to insure a tight joint between the spindle sleeve and the gear casing and to thereby prevent the escape of oil from the said gear casing. As above indicated, the said spindle sleeve is provided with an axial bore of substantially uniform diameter extending 130

its entire length and through the lower disk 20. Within the said bore is held a socket member 32, the same being provided at its inner end with diametrically arranged 5 grooves 32^a (Figs. 1 and 6) extending longitudinally of said socket member and adapted to engage similarly arranged projections 29^b formed on the inner surface of the spindle sleeve 29. The outer extremity 10 of the tool socket 32 is provided with a flange 32^b which abuts against the end of the spindle sleeve 29. A lock nut or cap 32^c extends over the end of the socket sleeve and the flange 32^b and engages the threaded 15 extremity of the spindle sleeve 29, said nut acting to hold the socket sleeve 32 within the spindle sleeve, and by its removal to permit the withdrawal of the said socket sleeve. The socket of the sleeve 32 is 20 slightly tapered to conform with the like taper of the shank of the tools to be held therein.

The central bore of the spindle sleeve by preference extends upwardly through the 25 disk 20 and within the upper portion of the bore is mounted the bearing for the lower end of the turbine shaft, said bearing comprising a plurality of cylindric rollers 33 mounted within a retaining cage 33^a. The 30 retaining cage rests upon a thrust plate 34 for the lower end of the turbine shaft, said plate being held from movement by its engagement with a retaining shoulder formed in said bore. The thrust plate 34 also acts 35 to hold the rotor shaft bearing in place.

Referring now to the construction and arrangement of the gears which are carried by the spindle and which transmit rotative movement from the turbine shaft to 40 the spindle: the same comprises two sets of speed reducing gear wheels each set consisting of two identical gear spindles 35, 35 and 36, 36 mounted within the hollow tool spindle and arranged diametrically opposite each 45 other on either side of the axis of the turbine shaft. Referring first to the gear spindles 35, 35 (Figs. 2 and 5), the same constitute the first set of reduction gears and comprise spur gear wheels 35^a, 35^a which 50 mesh with a central spur pinion 37 formed upon the surface of or fixed to the turbine shaft 5. The axes of these gears are parallel with that of said turbine shaft. Immediately below the large spur gear wheels 55 are smaller pinions 35^b, 35^b integral therewith. The gears 35^a are provided with journals or stub shafts 35^c which engage anti-friction roller bearings 38 and 39 mounted within annular recesses formed in 60 the upper and lower spindle disks 19 and 20, respectively. Meshing with the pinions 35^b of the gear spindles 35, are the gear wheels 36^a on the gear spindles 36 (Fig. 1) constituting the second set of reduction gears. 65 The gear wheels 36^a lie in the plane of the

pinions 35^b and below the plane of the gear wheels 35^a. The stub shafts 36^c, 36^c of the gear spindles 36, 36 are mounted at their upper ends in anti-friction bearings 40, 40 located in the upper spindle disk 19. The 70 portions of the said gear spindles 36, 36 below the spur gear wheels 36^a, however, are of a somewhat greater diameter than the stub shafts 36^c and extend downwardly through and beyond the lower spindle disk 75 20, the portions thereof below said disks having pinions 36^b cut upon their surfaces. (See Figs. 1 and 6.) The said pinions 36^b mesh with the stationary internal gear 6 secured within the gear casing, immediately 80 below the lower spindle disk 20. Roller bearings 41, 41 are mounted within the lower spindle disk and engage the bearing surfaces 36^d, 36^d of the portions of the gear spindles 36, 36 between the spur gear wheels 85 36^a, 36^a and the pinions 36^b, 36^b. In order to afford sufficient space to accommodate the large spur gear wheels 35^a, 35^a and 36^a, 36^a of the said gear spindles and portions of the spindle sleeve 21 are cut away, as shown 90 at 42, 42 of Figs. 1, 2 and 5. The adjacent faces of the upper and lower spindle disks 19 and 20 are preferably provided with washers 43 and 44, respectively, the same 95 acting to retain the several bearings in position.

The manner in which the power is transmitted from the rotor shaft to the tool spindle, by means of the arrangement of the said reduction gears, may be understood 100 from the following: The rotation of the turbine shaft which is turning at a high rate of speed is first transmitted to the gear spindles 35, 35 constituting the first set of reduction gears, by the intermeshing of the large 105 gear wheels 35^a, 35^a with the turbine shaft pinion 37. (See Figs. 1, 2 and 5.) From the gear spindles 35, 35, the rotative movement is transmitted to the gear spindles 36, 36 by the intermeshing of the gear 110 wheels 36 and the pinions 35^a, the speed of rotation of the gear spindles 36, 36 being substantially reduced by reason of the difference in the size of the said gear wheels 36^a, 36^a and pinions 35^b, 35^b. The rotative movement thus transmitted to the gear spindles 36, 36, acts to rotate the entire spindle 4, by reason of the intermeshing of the pinions 36^b, 36^b of the gear spindles 36, 36 and the stationary internal gear 115 6. (See Figs. 1, 5 and 6.) From this description, it is readily observed that the form of power transmission embodied in my invention partakes of the nature of a planetary drive and by the successive reductions 120 in speed of the tool spindle is suitable for the operation of the drilling tools carried thereby.

The air is supplied to the rotor by the following means: The upper portion of the 125 130

4

rotor casing is provided with an annular air passage 46 (Fig. 1) communicating with the inlet connection 47 and within which is placed a reducer fitting 48 provided at 5 its lower end with a strainer 48^a of fine wire mesh, for the purpose of preventing dirt and foreign matter from being carried into the tool. Within the reducing fitting 48 is secured a hose nipple 49, to which is attached the supply hose 49^a leading from a suitable source of motive fluid supply.

The air passage 46 communicates with two annular channels 50, 51 by means of two downwardly inclined passages 52 and 15 53, respectively, at the upper ends of which is located the throttle valve 10. (See Fig. 1.) The air channels 51, 52 are preferably formed by cutting grooves in a portion of the casing of increased thickness of metal 20 surrounding the rotor and fitting a ring 54 over the grooves, thereby converting the same into the said channels. The ring 54 is preferably provided with apertures communicating with each of the channels 50 25 and 51, and which are normally closed by means of screws 55, 55, having screw-threaded engagement therewith. By removing these screws, any particles of dirt which may have become lodged within the air 30 channels may be blown out by admitting air through the throttle valve. The channels 50 and 51 are separated by a partition wall 56 within which are formed a plurality of small air passages or nozzles 57 and 58 35 (Fig. 4). The nozzles or tangential passages 57 and 58 lie in a plane perpendicular to the axis of the rotor shaft and are in tangential relation to the rotor or at oblique angles with respect to the radii of the rotor. As illustrated in the drawings, the said nozzles are 40 arranged in two series of nozzles spaced at angles of 90° about the rotor casing. One of said series consists of four nozzles 57, which communicate with the channel 51 by 45 means of short vertical channels 57^a formed at the outer ends of the nozzles. These nozzles are inclined in the direction of the normal direction of rotation of the rotor tangentially with respect to the periphery of 50 the rotor. Thus a stream of motive fluid directed through the nozzles 57, strikes the concaved faces 2^b of the buckets 2^a of the rotor, rotating the same in the proper direction for operating the tool. The other 55 of said sets of nozzles 58 are spaced in similar relation about the rotor casing, each of the nozzles being located adjacent to a nozzle 57. Said nozzles 58, 58 are connected with the channel 50, by means of vertical passages 58^a (Fig. 1) at the outer ends thereof, and are also inclined tangentially with respect to the tangent to the periphery of the rotor but in a reverse direction from the inclination of the nozzles 57. Thus 60 streams of air from the nozzles 58 will

strike the convexed faces of the rotor buckets driving the rotor in a direction opposed to the normal direction of rotation.

In addition to the inlet passage for the motive fluid, an outlet is provided, which 70 assumes the form of a plurality of apertures 60 extending through the wall of the rotor casing and communicating with the outer atmosphere. The apertures are arranged in two series located above and below the plane 75 of the rotor and spaced evenly apart throughout substantially one-half the circumference of the rotor casing.

The throttle valve 10 before mentioned as located at the upper ends of the air passages 80 52, 53 and interposed between the said passages and the annular air passage 46, comprises the following elements: A cylindric valve chamber 10^a is formed integral with the rotor casing and within which is tightly 85 fitted a valve bushing 61 provided with a plurality of ports as follows: A large port 61^a (Fig. 1) located in the upper portion thereof and communicating with the air passage 46, and two smaller ports 61^b and 61^c 90 located diametrically opposite said port 61^a. The ports 61^b and 61^c are spaced a short distance apart circumferentially and are elongated in form. One of said ports 61^b registers with a similarly elongated recess 52^a 95 (Figs. 1 and 2), forming the upper extremity of the inclined air passage 52, and the other port 61^c in like manner communicating with the elongated recess 53^b of the air passage 53. Within the bushing 61 is 100 rotatably mounted the cylindric valve member 62 provided with a passage 63 extending diametrically through the central portion thereof. The said passage 63 is adapted to constantly register with the port 61^a of the 105 valve bushing 61 at one extremity and with either of the ports 61^b or 61^c at its other extremity, said latter extremity being provided with a longitudinally elongated mouth 63^a (Fig. 2) to correspond with the shape of the 110 ports 61^b and 61^c. The valve member 62 (Fig. 8) is provided at one end with a stem 62^a extending through and beyond the end wall of the bushing 61. Within the other end of the bushing is screwed a valve plug 115 64 provided at its inner end with a central depression 64^a within which is retained a spring 65 bearing against the adjacent end of the valve member 61 and acting to force the said valve member tightly against the 120 seat formed by the end wall of the bushing, thereby preventing a leakage of the motive fluid. Rigidly mounted upon the stem 62^a of the valve is the throttle lever 66 extending outwardly from the tool immediately below 125 the tool handle 9 in such a position as to be easily manipulated by the operator. The lever 66 is adapted to assume positions corresponding to the position of the passage 63 of the valve member relative to the ports 130

61^b, 61^c of the valve bushing, to wit: an open, a closed and a reversed position. When the lever is in the open position, the following conditions exist: The valve member 62 is in such a position that the passage 63 connects the main air passage 46 with the inclined air passage 52. Thus the motive fluid under pressure being admitted to the main air passage through the inlet connection 48, is carried through the valve and the air passage 52 into the lower channel 51, and thence through the nozzles 57, communicating with the said channel 51, and against the concaved faces of the rotor blades or buckets 2^b, the force of the streams of air issuing from the several nozzles 57 effecting the rotation of the rotor and turbine shaft at a high rate of speed, the direction of rotation of the rotor under the above described conditions being the proper one for operating the drill.

The closed position of the lever corresponds to the position of the valve member in which the passage 63 thereof registers at its lower end with a portion of the metal wall of the bushing 61 lying between the ports 61^b and 61^c. Obviously in this position the air is entirely cut off.

The reversed position of the lever corresponds to the position of the valve in which the passage 63 connects the main air passage 46 and the port 61^b of the valve bushing, thus the air is free to pass into the inclined air passage 53 which communicates with the upper air channel 50 and thence through the nozzles 58. The air issuing from said nozzles 58 strikes the rotor blades upon their convex surfaces, thus retarding the rotation of the turbine or rotor effecting the rotation of the turbine rotor and shaft in the reverse direction, that is, in the opposite direction from that produced by the air issuing from the nozzles 57, under which circumstances the lever is in the open position.

It is at once apparent that the driving effect or the power transmitted to the rotor is very much less when the rotor is moving in the reverse or backward direction than when it is running in the proper or forward direction, due to the fact that the air strikes the convexed faces of the rotor blades and a considerable loss of power must necessarily result. In view of this fact, it is to be understood that the real purpose of reversing the direction in which the motive fluid strikes the rotor blades is to provide a means that shall effectively act as a brake, rather than that the turbine shall be operated in either direction of rotation. The need of such a braking means is more apparent when the fact is brought to mind that were the load to be taken off the tool while driving in the normal direction of rotation and then the motive fluid entirely shut off, the turbine

for a considerable length of time, so well balanced are the several parts. Under such circumstances it would be impractical to stop the rotation of the turbine by the application of a frictional braking means, 70 owing to the excessive wear that would result, nor would it be practical to attempt to stop its rotation by grasping the end of the spindle or tool with the hand because of the liability of injury.

In order to provide means whereby the lever 66 will be prevented from remaining in reversed position except when pressure is applied to it by the operator, the following construction is preferably employed: 80 The lever is provided with a projecting finger 66^a extending inwardly beyond the axis of the valve member and moving within a narrow semicircular shaped recess 67 (Fig. 7) formed in the casing. Communicating with the upper end of said recess is a vertically arranged, cylindrical bore 68 opening against the bottom face of the base plate 9^a of the tool handle 9. Within this bore is mounted an endwise movable plunger 69 90 provided with a central depression within which is retained a coiled spring 70. The spring bears against the said base plate 9^a of the tool handle and acts to constantly force the plunger downwardly. A shoulder 95 68^a formed at the bottom of the bore 68 limits the downward movement of the plunger. In the closed position of the lever 66, the finger 66^a is in contact with the plunger in its extreme downward position. Thus 100 the plunger normally acts as a stop for the lever at the closed position thereof. However, if it is desired to stop the rotation of the turbine, the lever is forced downwardly against the pressure of the plunger to the 105 reverse position, and remains in that position until the lever is released by the operator, in which case the plunger acts upon the finger 66^a forcing the lever to the closed position. To move the lever to the open 110 position, the same is swung upwardly to approximately a vertical position, the finger at the same time moving downwardly and free from contact with the plunger 69. A stop pin 71 is preferably provided at the 115 lower extremity of the recess and engages the finger 66^a of the lever at the open position of the same. It is to be understood that the handle may be replaced by a breast plate or a feed screw mechanism for bracing the 120 tool if desired.

By the construction of a turbine as hereinbefore described, several important features are disclosed which add greatly to the practical use of tools of this type. One of such features is the introduction of the planetary form of power transmission embracing the spindle and the reduction gearing carried by the same. It is to be noted that the entire spindle is arranged in a symmetrical man- 130

6
ner about the turbine shaft, that is to say, the gears are all arranged in pairs located diametrically opposite each other on either side of the turbine shaft, the weight of one 5 acting to counterbalance the weight of the other, and in like manner the driving effort of the turbine shaft is transmitted to the spindle at two diametrically opposite points. The obvious advantage of this construction is that a perfectly balanced mechanism is obtained, whereby the highest possible efficiency is the result owing to the small amount of friction produced. Furthermore the use of this particular form 10 of power transmission permits the use of a high speed turbine, the speed being reduced to the proper working speed in the most efficient manner. The added weight of the reduction gears carried by the spindle is 15 particularly advantageous in this instance, for the reason that the inertia is increased to such an extent as to produce a fly-wheel effect and relieve the turbine shaft of sudden jars or shocks such as are often experienced in the operation of tools of this class 20 and which would be injurious to the parts rotating at a high rate of speed. The high rate of speed at which the turbine shaft is capable of rotating in my device is largely 25 due to the arrangement of the nozzles 57, in that they are not only spaced about the circumference of the casing but that the air strikes the blades at a tangent to the circumference of the rotor and not from the side 30 as is often the arrangement in turbines of this class. The advantage of this construction 35 is that the rotor is perfectly balanced in all directions so that there is no tendency for the turbine shaft to be shifted laterally 40 or endwise so as to increase the friction and consequently decrease the speed obtainable. The arrangement of the two sets of nozzles, one of which directs the air against the turbine blades in a direction to reverse the normal 45 direction of rotation, is a feature which permits the utilization of air as a brake to stop the rotor. One advantage of this form of brake is that it eliminates the use of all frictional brake devices which are objectionable in that a replacement of the parts 50 is frequently required on account of the wear. Numerous other features are embodied in my invention, all of which combine to make the device a very compact, efficient and serviceable tool for drilling or like 55 purposes.

I am aware that the construction of my device may be variously modified in its details without departing from the spirit of 60 my invention, and for that reason do not wish to be limited to the structure herein described or illustrated in the accompanying drawings, except in so far as it is specifically set forth in the appended claims.

I claim as my invention:

65

1. In a pneumatic turbine drill, the combination of a casing, a rotor, a rotor shaft provided with a pinion, a tool spindle surrounding said rotor shaft and supporting one end thereof, a rotary gear wheel carried by said tool spindle and meshing with said rotor shaft pinion, a fixed gear, a pinion carried by said tool spindle and meshing with said fixed gear, and means for operatively connecting said last mentioned pinion 75 with said rotary gear.

2. In a pneumatic turbine drill, the combination of a rotor, a rotor shaft provided with a pinion, a rotative tool spindle in axial alinement with said rotor shaft and forming 80 a support for one end of said rotor shaft, a rotary gear wheel carried by said tool spindle and in toothed engagement with said rotor shaft pinion, a fixed gear, a pinion carried by said tool spindle and in toothed 85 engagement with said fixed gear, and intermeshing gear members operatively connecting said rotary gear wheel with the pinion carried by said tool spindle.

3. In a pneumatic turbine drill, the combination of a casing provided with a rotor chamber, a rotor mounted within said rotor chamber, a gear casing, a rotor shaft, a tool spindle rotatively mounted in said gear casing, and forming a bearing for one extremity of said rotor shaft, an annular disk separating said rotor chamber and gear casing, a bearing on said disk and in engagement with the rotor shaft, and speed reducing gearing carried by said tool spindle and 90 in engagement with said rotor shaft and with said tool spindle.

4. In a pneumatic turbine drill, the combination of a rotor casing, a rotor in said rotor casing, a gear casing, a spindle bearing supporting member, a rotor shaft extending through said supporting member and into said gear casing, a tool spindle in said gear casing surrounding the portion of said rotor shaft within the gear casing, a 105 pinion on said rotor shaft, a rotor shaft bearing supported by said tool spindle, a fixed gear mounted in said gear casing, and speed reducing gearing carried by said tool spindle and in driving engagement with 110 said rotor shaft pinion and said fixed gear.

5. In a pneumatic turbine drill, the combination of a casing, a rotor, a rotor shaft provided with a pinion, a tool spindle, a bearing supported by the tool spindle and in engagement with one extremity of said rotor shaft, an internal gear fixed to said casing, a rotary gear wheel carried by said tool spindle and meshing with the rotor shaft pinion, a pinion turning with said 120 rotary gear wheel, a second gear wheel carried by said tool spindle and meshing with the said last mentioned pinion and provided 125

with a pinion in toothed engagement with said internal gear.

6. In a pneumatic turbine drill, the combination of a rotor casing, a rotor mounted within said rotor casing, a gear casing, an annular disk separating said rotor and gear casings, a rotor shaft, extending through said annular disk and provided with a pinion, a tool spindle rotatively mounted in said gear casing, and comprising two spindle disks one of said disks being provided with a bearing flange surrounding said rotor shaft, a bearing supported in said annular disk and engaging the said bearing flange, the other of said spindle disks supporting a bearing for said rotor shaft, a spindle sleeve integral with said last mentioned disk and extending through said gear casing, an internal gear fixed in said gear casing, and speed reducing gearing carried by said tool spindle and in driving engagement with said rotor shaft pinion and said internal gear.

7. In a pneumatic turbine drill, the combination of a rotor casing, a rotor in said rotor casing, a gear casing, a fixed bearing supporting member intermediate said rotor and gear casings, a rotor shaft extending through said fixed bearing supporting member and into said gear casing, a tool spindle mounted in said gear casing comprising two transverse spindle members, a pinion on said rotor shaft, a rotor shaft bearing supported by one of the transverse spindle members, a fixed gear mounted in said gear casing, and speed reducing gearing carried by said tool spindle and located between and supported by the transverse spindle members, and in engagement with said rotor shaft pinion and said fixed gear.

8. In a pneumatic turbine drill, the combination of a casing, a rotor, a rotor shaft provided with a pinion, an internal gear fixed to said casing, a tool spindle, a gear wheel carried by the tool spindle and meshing with the rotor shaft pinion, a pinion integral with said gear wheel, a gear wheel meshing with the said last mentioned pinion, and a shaft integral with said last mentioned gear wheel and provided at its end with a pinion meshing with said internal gear.

9. In a pneumatic turbine drill, the combination of a rotor, a rotor shaft provided with a pinion, a tool spindle in axial alignment with the rotor shaft, an internal gear fixed to said casing, a plurality of pairs of diametrically opposed gear wheels carried by said tool spindle, each of said gear wheels being provided with a pinion in axial alignment and turning therewith, one of said pairs of gear wheels meshing with the rotor shaft pinion, the other pair of gear wheels meshing with the pinions of the first mentioned pair of gear wheels, and the

pinions of said last mentioned pair of gear wheels meshing with the said internal gear.

10. In a pneumatic turbine drill, the combination of a casing, a rotor, an internal gear fixed to said casing, a rotor shaft provided with a pinion, a tool spindle comprising two spindle disks secured in fixed relation, a gear wheel mounted between said spindle disks and meshing with the rotor shaft pinion, a pinion fixed to said gear wheel, a gear wheel located between said disks and meshing with said last mentioned pinion, a shaft fixed to said last mentioned gear wheel and extending through one of said spindle disks, and a pinion on said shaft and in toothed engagement with said internal gear.

11. In a pneumatic turbine drill, the combination of a casing, a rotor, an internal gear fixed to said casing, a rotor shaft provided with a pinion, a tool spindle comprising two spindle disks secured in fixed relation, a gear wheel mounted between said spindle disks and meshing with the rotor shaft pinion, a pinion fixed to said gear wheel, a gear wheel located between said disks and meshing with said last mentioned pinion, a shaft fixed to said last mentioned gear wheel and extending through one of said spindle disks, a pinion on said shaft and in toothed engagement with said internal gear, and a spindle sleeve fixed to one of said spindle disks and extending through the wall of the casing.

12. In a pneumatic turbine drill, the combination of a rotor, a rotor shaft provided with a pinion, a tool spindle in axial alignment with the rotor shaft, an internal gear fixed to said casing, a pair of gear wheels carried by said tool spindle and meshing with the rotor shaft pinion at diametrically opposite points, each of said gear wheels being provided with a pinion in axial alignment and turning therewith, and gearing interposed between said pinions of the gear wheels and said internal gear.

13. In a pneumatic turbine drill, the combination of a casing, a rotor, a rotor shaft provided with a pinion, an internal gear fixed to said casing, and a tool spindle comprising two transverse spindle members in axial alignment with the rotor shaft, a gear wheel mounted between said transverse spindle members and provided with a stub shaft, a pinion at the end of said stub shaft meshing with said internal gear, and driving means interposed between and operatively connected with said gear wheel and the pinion of the rotor shaft.

14. In a pneumatic turbine drill, the combination of a casing, a rotor, a rotor shaft provided with a pinion, a tool spindle comprising two spindle disks secured in fixed relation to each other, a plurality of pairs of gear spindles mounted in said spindle disks,

one of said pairs of gear spindles being provided with gear wheels and pinions located between said disks, said gear wheels meshing with the rotor shaft pinion at points thereof 5 diametrically opposite, the other pair of gear spindles having projecting end portions extending through one of said spindle disks and being provided with gear wheels located between said spindle disks and meshing with 10 the pinions of the first mentioned pair of gear spindles, and pinions at the extremities of the last mentioned pair of gear spindles and located beyond the disk through which said projecting gear spindles extend, and an 15 internal gear fixed to said casing and in toothed engagement with the pinions of the last mentioned pair of gear spindles.

15. In a pneumatic turbine drill, the combination of a casing, a rotor provided with 20 radially extending blades or buckets, a channel surrounding said rotor, a nozzle communicating with said channel and the casing, said nozzle being adapted to direct the motive fluid against the said buckets, and a plurality of annularly arranged exhaust openings 25 in the wall of the casing located at either side of the channel.

16. In a pneumatic turbine drill, the combination of a casing, a rotor provided at its 30 periphery with radially extending blades, a plurality of nozzles lying in the plane of said rotor, said nozzles being oppositely inclined with respect to the axis of said rotor and adapted to direct the motive fluid against 35 the said blades to effect the rotation of the rotor in either direction, and a series of annularly arranged exhaust openings in the wall of the casing and located at either side of the plane of the rotor.

40 17. In a pneumatic turbine drill, the combination of a casing, a rotor provided at its periphery with radially extending blades, a plurality of nozzles formed in said casing and lying in the plane of said rotor, said 45 nozzles being oppositely inclined to the axis of said rotor to direct the motive fluid against the said blades to effect the rotation of the rotor in either direction, a throttle valve for controlling the flow of the motive 50 fluid into either of said nozzles, and means acting on said throttle valve to prevent the flow of the motive fluid into one of said channels, except when a constant pressure is applied to said throttle valve.

55 18. In a pneumatic turbine drill, the combination of a casing, a rotor provided at its periphery with radially extending blades, a plurality of channels formed in said casing surrounding said rotor, a partition wall 60 separating said channels, a plurality of nozzles formed in said partition wall and communicating with said channels and the interior of the casing, said nozzles communicating with each of said channels being oppositely inclined to the axis of said rotor, to

direct the flow of the motive fluid against opposite faces of the said rotor blades, and a throttle valve adapted to control the flow of the motive fluid to either of said air channels.

19. In a pneumatic turbine drill, the combination of a casing, a rotor within said casing provided with a plurality of blades, a plurality of annular channels surrounding said rotor, a plurality of nozzles communicating with each of said channels, the said nozzles communicating with one of the channels being similarly inclined to the axis of the rotor to direct the motive fluid against the rearward surfaces of the blades, for 70 driving the rotor in one direction, and the nozzles communicating with the other of said channels being oppositely inclined with respect to the axis of the rotor and adapted to direct the motive fluid against the opposite surfaces of the blades, a throttle valve adapted to control the flow of motive fluid to the said channels, and provided with an operating lever, and means acting on said lever to prevent the flow of the motive fluid 80 against the rearward surfaces of the blades except when pressure is being applied to the 85 said operating lever.

20. In a pneumatic turbine drill, the combination of a casing, a rotor within said 95 casing provided at its periphery with radially extending blades, a plurality of annular channels surrounding said rotor, a plurality of nozzles communicating with said channels to direct the motive fluid against 100 the blades, the said nozzles communicating with one of the channels lying in the plane of the rotor and inclined at an angle to the axis of the rotor to effect the rotation of the rotor in one direction, and the nozzles communicating with the other of said channels, also lying in a plane of the rotor and inclined at an angle to the axis of the rotor to effect the rotation of the rotor in the opposite direction, a manually operable throttle 105 valve adapted to control the flow of motive fluid to the said channels, and means for preventing the flow into one of said channels except when pressure is being applied to the 110 said valve.

21. In a pneumatic turbine drill, the combination of a rotor casing, a rotor provided with radially extending blades, a rotor shaft, a series of nozzles lying in the plane of the rotor and oppositely inclined to the axis of said rotor shaft and adapted to direct the flow of the motive fluid to drive the rotor in either direction, means for controlling the flow of the motive fluid to either series of nozzles, and a plurality of exhaust 120 openings in said casing arranged in a plane parallel and adjacent to the plane of the rotor.

22. In a pneumatic turbine drill, the combination of a rotor casing, a rotor provided 125

with radially extending blades, a rotor shaft provided with a pinion, a series of nozzles lying in the plane of the rotor and oppositely inclined with respect to the axis of 5 said rotor shaft to direct the flow of the motive fluid to drive the rotor in either direction, means for controlling the flow of the motive fluid to either series of nozzles, a gear casing, an annular disk interposed between 10 said rotor casing and said gear casing, a rotative tool spindle mounted in said gear casing, a fixed internal gear within said gear casing, a bearing for said spindle supported in said annular disk and said gear casing, 15 bearings for said rotor shaft supported in said rotor casing and said tool spindle, and speed reducing gearing carried by said tool spindle and interposed between the internal gear and the rotor shaft pinion.

20 23. In a pneumatic turbine drill, the combination of a rotor casing, a rotor, a rotor shaft carrying said rotor and provided with a bearing in said rotor casing and a pinion, a gear casing, a rotative tool spindle mounted 25 in said gear casing, a spindle bearing support secured between the adjacent margins of the said rotor and gear casings, a clamping ring engaging the margins of said rotor and gear casings, a bearing in said spindle 30 for the rotor shaft, an internal gear fixed in said gear casing, and speed reducing gears carried by said spindle and in driving engagement with said internal gear and the pinion of the rotor shaft.

35 24. In a pneumatic turbine drill, the combination of a rotor casing, a rotor, a rotor shaft carrying said rotor and provided with a bearing in said rotor casing and a pinion, a gear casing, a rotative tool spindle mounted 40 in said gear casing, an annular disk support mounted between the adjacent margins of the said rotor and gear casings, a spindle bearing supported in said disk, a clamping ring in screw-threaded engagement with the 45 margins of said rotor and gear casings, a bearing in said spindle for the rotor shaft, an internal gear fixed in said gear casing, and speed reducing gears carried by said spindle and meshing with said internal gear 50 and with the pinion of the rotor shaft.

55 25. In a pneumatic turbine drill, the combination of a rotor casing, a rotor, a rotor shaft carrying said rotor and provided with a bearing in said rotor casing and a pinion, a gear casing, a rotative tool spindle in said gear casing, an annular disk mounted between 60 said rotor casing and gear casing, and supporting a bearing for one end of said tool spindle, a thrust bearing mounted between 65 said annular disk and tool spindle, a spindle sleeve integral with said spindle and extending through the wall of said gear casing, a bearing engaging said sleeve, an internal gear fixed in said gear casing, and speed 70 reducing gears carried by said tool spindle

and meshing with said internal gear and the pinion of the rotor shaft.

26. In a pneumatic turbine drill, the combination of a rotor casing, a rotor, a rotor shaft carrying said rotor and provided with a bearing in said rotor casing and a pinion, a gear casing, a rotative tool gear spindle in said gear casing, an annular disk mounted between said rotor casing and gear casing and supporting a bearing for one end of said tool spindle, a thrust bearing mounted between 75 said annular disk and tool spindle, an internal gear fixed in said gear casing, and speed reducing gears carried by said tool spindle and meshing with said internal gear 80 and the pinion of the rotor shaft.

27. In a pneumatic turbine drill, the combination of a casing, a rotor, a rotor shaft, a tool spindle in axial alignment with said rotor shaft and provided with a bearing for 85 one extremity of said shaft, a sleeve integral with said spindle and extending through the wall of the casing, said sleeve having a central bore of uniform diameter provided upon its surface with a longitudinal projection, a tool-holding member fitting within said bore and provided with a longitudinal groove adapted to engage said lug of the spindle sleeve and a lock nut in screw-threaded engagement with the end of said 90 spindle sleeve and bearing against said socket sleeve to hold the same within the spindle sleeve.

28. In a power actuated drill, the combination of a casing, a rotor, a tool spindle 100 mounted in the casing in operative connection with the rotor, a sleeve integral with said tool spindle extending through the wall of the casing, said sleeve having an axial bore of uniform diameter provided upon its 105 surfaces with a plurality of oppositely disposed, longitudinal projections, a tool-holding member fitting within the said bore and provided with longitudinal grooves adapted to be engaged by said projections, and with 110 an annular flange abutting against the end of the sleeve, and a lock-nut having screw-threaded engagement with the end of the sleeve and bearing against the said lock-nut.

29. In a pneumatic turbine drill, the combination of a casing, a rotor provided with radially extending blades, a plurality of passages surrounding said rotor lying in the plane of the rotor and inclined at an angle to the axis thereof, said passages being 120 adapted to direct the motive fluid against one face of the blades to drive the rotor in a direction for the normal operation of the tool, and a brake comprising a passage adapted to direct the motive fluid against 125 the opposite face of the said blades, a throttle valve for controlling the flow of the motive fluid to such passages, and means acting on said throttle valve to prevent the flow of the motive fluid against said opposite face 130

of the blade except when a constant pressure is applied to said throttle valve.

30. In a pneumatic turbine drill, the combination of a casing, a rotor provided with 5 radially extending blades, a plurality of passages surrounding said rotor lying in the plane of the rotor and inclined at an angle to the axis thereof, said passages being adapted to direct the motive fluid against 10 one face of the blades to drive the rotor in a direction for the normal operation of the tool, and a brake comprising a passage adapted to direct the motive fluid against the opposite face of the said blades, a throttle valve for controlling the flow of the motive fluid to said passages, and means acting on 15 said valve to prevent the flow of the motive fluid to said last mentioned passage except when a constant pressure is being applied to the lever of said valve.

31. In a pneumatic turbine drill, the combination of a casing, a rotor mounted in said casing and provided at its periphery with a plurality of radially extending blades, a plurality 25 of channels comprising grooves formed in said casing and surrounding said rotor, said grooves being separated by an annular partition wall, and a ring surrounding said casing and said grooves, a series of 30 nozzles formed in said partition wall and communicating with each of said channels,

each of said series of nozzles being oppositely inclined at an angle to the axis of the rotor to direct the flow of the motive fluid to rotate the rotor in opposite directions, 35 and a throttle valve for controlling the flow of the motive fluid in said channels.

32. In a pneumatic turbine drill, the combination of a casing, a rotor provided with radially extending blades, a plurality or 40 series of nozzles in said casing, said series of nozzles being oppositely inclined at angles to the axis of the rotor to direct the flow of the motive fluid to rotate the said rotor in either direction, passages communicating 45 with said series of nozzles, and a throttle valve interposed between said passages and the source of supply and comprising a movable valve member, a throttle lever, and a spring actuating plunger acting on said 50 throttle lever to prevent the continued flow of the motive fluid to one of said passages except when a constant pressure is applied to the throttle lever.

In testimony, that I, claim the foregoing 55 as my invention I affix my signature in the presence of two witnesses, this 4th day of September, A. D. 1913.

REINHOLD A. NORLING.
